UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

SKIVING-MACHINE.

1,247,780.

Specification of Letters Patent. Patented Nov. 27, 1917.

Application filed March 29, 1915. Serial No. 17,860.

To all whom it may concern:

Be it known that I, ALEXANDER M. ALEXANDER, a citizen of the United States, residing at Beverly, in the county of Essex and State of Massachusetts, have invented certain new and useful Improvements in Skiving-Machines; and I do hereby declare the following to be a full, clear, and exact description of the invention, such as will enable others skilled in the art to which it appertains to make and use the same.

The present invention relates to leather skiving machines and more particularly to machines of this character which comprise a rotary skiving knife and coöperating gage and presser members for guiding and feeding the work to the knife.

The object of the present invention is to improve the construction and operation of certain portions of a skiving machine of this character to render the operation of the machine more certain and reliable and improve the quality of the work performed thereby.

With this end in view one feature of the invention contemplates the provision in a machine of this type having a tubular skiving knife and means for rotating the knife, of coöperating gage and presser members engaging with the work upon opposite sides of the knife, a member for grinding a bevel face upon one surface to put the cutting edge at the opposite surface of the knife, and a second grinding member engaging with the opposite surface of the knife to remove eccentricities from the surface.

Still further features of the invention consist in certain novel features of construction, combinations, and arrangements of parts hereinafter described and claimed, the advantages of which will be obvious to those skilled in the art from the following description.

In the accompanying drawings illustrating the preferred form of the invention; Figure 1 represents an end elevation of a machine embodying the several features of the invention; Fig. 2 is a view representing a partial front elevation of the machine shown in Fig. 1; Fig. 3 is a view showing a

longitudinal section in plan of the mechanism shown in Fig. 1; Fig. 4 is a view showing a longitudinal section in elevation of the mechanism; Fig. 5 is a detail view illustrating a side view of the mechanism for supporting and adjusting the truing wheel; Fig. 6 is a detail showing an end elevation partly in section of the mechanism shown in Fig. 5; and Fig. 7 is a detail showing a section upon the line 7—7 of Fig. 5.

60

The machine shown in the illustrated embodiment of the invention is of the general type shown and described in the patent to Alexander No. 1,117,541, granted November 17, 1914. This machine comprises a tubular skiving knife 1 journaled in the machine frame 2 and having a knife blade 3 which is clamped in a substantially cylindrical knife holder 4 in the usual manner. The work is guided and fed into operative relation to the skiving knife by a gage member 5 which is supported by an overhanging arm 6 and coöperates with a rotary feeding and pressing roll 7 supported within the knife. The feed roll is journaled in a roll carrying head 8 and has provision for a bodily yielding movement toward and from the knife edge, and an angular tipping movement about one end. In addition, the roll carrying head may be oscillated about the supporting shaft 9 to vary the working portion of the roll and is locked in any adjusted position by an arm 10 projecting radially from the shaft and engaging with a locking plate 11, as shown clearly in Fig. 1.

65

80

It is extremely important in machines of this type that the cutting edge of the knife shall conform accurately to the true circle of rotation of the knife, thus enabling the machine to operate most efficiently upon all kinds of material and form an even, uniform bevel surface. To this end, in the present invention improved mechanism permanently embodied in the machine is provided for grinding a bevel cutting face upon the outer surface of the knife to put the cutting edge at the opposite surface and for removing the eccentricities upon the inner surface of the knife without forming any substantial bevel upon this surface. In the illustrated em- 100

85

90

95

bodiment of the invention a grinding disk is supported in operative relation to the outer surface of the knife to form a bevel cutting face thereon and a second grinding member 5 is permanently located in operative relation to the inner surface of the knife and is arranged to engage with the surface in a substantially straight line path of contact extending in the direction of the axis of the 10 knife. With this construction the gage member and feed roll are positioned at the top portion of the knife and the grinding members are permanently positioned at opposite sides of the knife during the operation of the 15 machine, thus enabling the grinding operation to be performed whenever desired without modifying or changing the machine in any manner. The bevel cutting face is formed upon the outer surface by a grinding 20 disk 12 journaled upon a head 13 at one side of the knife and rotated and moved into and out of operative relation with the knife as fully described in the application above referred to. In addition to this outer grinding 25 member a grinding disk 14 is supported in operative relation to the inner surface of the knife at the opposite side to true up the inner surface of the knife, as clearly shown in Fig. 1 of the drawings. The grinding disk 30 14 is supported with its axis substantially parallel to the axis of the knife when in operative relation with the knife, and the periphery of the grinding disk engages with the inner surface of the knife in a substantially 35 straight line path of contact extending in the direction of the axis. In order to improve the grinding action and insure that the contact between the grinding disk and the knife shall be in a straight line path, 40 mechanism is provided for moving the disk in a rectilinear path extending in the direction of the knife axis. To this end the grinding disk 14 is mounted upon the end of a shaft 15 slidably supported in a bracket 16 45 which is fulcrumed upon a stationary head 17 at 18 and is normally retained in an inoperative position by a spring 19 interposed between the machine frame and the bracket 16, as shown clearly in Fig. 3. The bracket 50 16 is oscillated to move the grinding disk into engagement with the knife blade by an adjusting stem 20 pivotally connected to the bracket at one end and having a knurled operating nut 21 threadedly mounted upon 55 the opposite end and engaging with the machine frame to draw the grinding disk into contact with the knife blade in the usual manner. It will be obvious to those skilled in the art that the provision of the adjusting 60 nut 21 forms a gage for positively determining the position of the grinding disk with relation to the knife, and serves to limit the movement of the grinding disk in a direction away from the surface of the knife. For 65 convenience of operation, and to prevent the

formation of a shoulder upon the inner surface of the knife, the axis of the grinding disk may be positioned at a very slight inclination to the axis of the knife, as shown clearly in the drawings, without, however, 70 forming any substantial bevel upon the inner surface of the knife which would tend to prevent the work being pressed against the gage member by the knife edge. When in operative relation to the surface of the knife 75 the grinding disk is moved axially by sliding the shaft 15 in the supporting bracket 16 and this is conveniently accomplished by a knurled handle 22 mounted upon the outer end of the shaft. The grinding disk is conveniently rotated by connections from the end of the knife shaft through a shaft 27 supported concentrically with the knife shaft and connected thereto through a pair of coöperating clutch faces indicated at 26. 80 The shaft 27 is slidably supported in the bearings and may be moved into and out of engagement with the end of the knife shaft by a knurled handle 28. The grinding disk shaft 15 is actuated from the drive 90 shaft 27 through pulleys 23 and 24 splined respectively to the two shafts and connected by a crossed drive belt 25 to rotate the grinding disk in a direction opposite to the direction of rotation of the knife. With this construction it will be observed that both of the 95 grinding disks are permanently embodied in the machine and may be conveniently brought into operative relation to the skinning knife to maintain a true cutting edge 100 upon the knife without the necessity of disturbing any of the other elements of the machine.

In this type of machine the grinding disk is used more or less constantly to maintain 105 a sharp cutting edge and as these grinding members necessarily vary somewhat in hardness throughout the mass it is advisable to provide mechanism for conveniently truing up the peripheral surface of the disk in order that it may perform the grinding operation in the best manner. In the present invention, the outer grinding disk performs the greater portion of the work and to this 110 end a truing wheel is supported in operative relation to this disk and is provided with mechanism under the control of the operator for traversing it back and forth across the periphery of the disk to even the surface and remove any inequalities which 115 may be present. In the illustrated embodiment of the invention a truing wheel 37 is permanently supported to rotate about an axis parallel to the axis of the grinding wheel and is moved axially to traverse it 120 back and forth across the periphery of the wheel. The truing wheel is journaled upon the upper end of a spindle 38 slidably supported in a head 39 which is adjustably secured to the bracket 13 of the grinding disk. 125 130

The head 39 is supported and guided by projecting bolts 40 secured in the bracket 13 and received in parallel slots 41 formed in the head. The movement of the truing wheel toward and from the grinding disk is accomplished by an adjusting rod 42 threadedly engaging with a split sleeve 43 formed upon the bracket 13 and arranged to frictionally retain the rod 42 in any adjusted position by a clamping bolt 44. The adjusting rod 42 is connected to the head 39 by a pair of lugs 45 projecting from the head and embracing a collar 46 secured to the rod, thus causing a lengthwise movement of the rod to impart a like movement to the head. The adjusting rod is conveniently manipulated by a knurled member 47 supported upon the outer end. After the truing wheel has been moved into engagement with the periphery of the grinding disk it is traversed back and forth across the disk by an operating arm 48 projecting into a position conveniently accessible to the operator and loosely sleeved upon the adjusting rod 42, as shown clearly in Fig. 3. The arm 48 is connected to the spindle of the truing wheel through a second arm 50 projecting from the sleeve 51, having a bifurcated outer end which embraces a pin 53 mounted in the lower end of the spindle, as shown clearly in Fig. 1.

While it is preferred to employ the specific construction and arrangement of parts shown and described, it will be understood that this construction and arrangement is not essential except so far as specified in the claims, and may be changed or modified without departing from the broader features of the invention.

40 The invention having been described, what is claimed is:—

1. A skiving machine, having in combination, a tubular skiving knife, means for rotating the knife, coöperating gage and 45 presser members to guide the work to the knife, a grinding member for forming a bevel cutting face upon the outer surface of the knife to put the cutting edge at the opposite surface, and a second grinding 50 member constructed and arranged to engage with and remove eccentricities in the inner surface of the knife and form a true cutting edge without forming any substantial bevel thereon.

55 2. A skiving machine, having in combination, a tubular skiving knife, means for rotating the knife, coöperating gage and presser members for guiding the work to the knife, a grinding member arranged to 60 form a bevel cutting face upon the outer surface of the knife to put the cutting edge at the opposite surface of the knife, and a second grinding member positioned in operative relation to the inner surface of the 65 knife and engaging with the surface in a

substantially straight line path of contact extending in the direction of the axis of the knife to remove eccentricities in the surface.

3. A skiving machine, having in combination, a tubular skiving knife, a knife shaft, coöperating gage and presser members for guiding the work to the knife, a grinding disk engaging with the inside of the knife, a shaft for driving the grinding disk supported concentrically with the knife shaft, means for moving the grinding disk drive shaft into and out of operative relation to the knife shaft, and connections between the drive shaft and grinding disk. 70

75 4. A skiving machine comprising a tubular skiving knife, means for rotating the knife, an oscillatory bracket, a grinding disk journaled in the bracket adjacent to the surface of the knife, means for actuating the bracket to move the periphery of the grinding disk into contact with the surface of the knife, and means for moving the grinding disk axially. 80

85 5. A skiving machine comprising a tubular skiving knife, a knife shaft, a grinding disk, a shaft supporting the grinding disk in operative relation to the surface of the knife, a drive shaft, means for moving the drive shaft into and out of operative relation to the knife shaft, connections between the drive shaft and grinding disk, and means for moving the grinding disk axially. 90

95 6. A skiving machine comprising a tubular skiving knife, coöperating gage and presser members for guiding the work to the knife, a grinding disk engaging with the outer surface of the knife to form a bevel cutting face and place the cutting edge at the opposite surface of the knife, a second 100 grinding disk engaging with the inner surface of the knife in a substantially straight line path of contact extending in the direction of the axis, and mechanism for moving the second grinding disk in a rectilinear 110 path extending in the direction of the axis of the knife. 105

115 7. A skiving machine, having in combination, a cylindrical skiving knife, a gage member and a presser member coöperating to feed the work to the knife, a grinding disk operatively engaging with the knife, a truing member positioned in operative relation to the grinding disk, and mechanism for moving the truing member into engagement 120 with the grinding disk and for traversing the truing member across the periphery of the grinding disk. 125

130 8. A skiving machine comprising a rotary skiving knife, a grinding disk positioned in operative relation to the knife, a head, a truing wheel journaled in the head in operative relation to the grinding disk, means for adjusting the head to move the truing wheel toward and from the grinding disk, and

means for moving the truing wheel axially to traverse it back and forth across the periphery of the grinding disk.

9. A skiving machine comprising a rotary skiving knife, a grinding disk supported in operative relation to the knife, a head, a truing wheel journaled upon the head, mechanism for adjusting the head, an operating

arm, and connections between the arm and truing wheel to impart an axial movement 10 to the truing wheel upon moving the arm.
